UNITED STATES PATENT OFFICE.

GEORGE J. RAUPP AND DAVID CORNFOOT, OF BUFFALO, NEW YORK.

PIANO BENCH.

Application filed August 16, 1922. Serial No. 582,155.

To all whom it may concern:

Be it known that we, GEORGE J. RAUPP and DAVID CORNFOOT, citizens, respectively, of the United States and of Great Britain, residing at Buffalo, in the county of Erie and State of New York, have invented certain new and useful Improvements in Piano Benches; and we do hereby declare the following to be a full, clear, and exact description of the invention, such as will enable others skilled in the art to which it appertains to make and use the same.

The present invention relates to improvements in benches for use in connection with pianos, etc.

The primary object of this invention is to provide a bench with a compartment which is adapted for holding music rolls such as are used with player pianos; another object is to provide said roll holders with a lower stationary portion as a means of storing the little used rolls, while movable upper roll holders are used for the rolls in more constant use; another object is to provide said movable holders in a size and form to be easily removed from said compartment and to hold said rolls in such a manner as to form a convenient filing system without the use of cards or like devices.

A further object is to provide a piano bench of the character described adapted to normally have the top in a horizontal position when not in use or for playing a non-automatic piano and also for tilting the top at a desirable angular position for playing a player piano.

With the foregoing and other objects in view which will appear as the description proceeds, the invention consists of certain novel details of construction and combination of parts which will be hereinafter more fully described and pointed out in the claims, it being understood that various changes may be made in the construction and arrangement of the parts without departing from the spirit or sacrificing any of the advantages of the invention as set forth in the appended claims.

Referring to the accompanying drawings, wherein like symbols refer to like or corresponding parts throughout the several views,

Figure 1, is a plan of an improved piano

bench constructed according to the present invention;

Fig. 2, is a front elevation of the bench with a portion broken away;

Fig. 3, is a side elevation of the bench with the top shown tilted for use with a player piano and with the top shown dotted in a raised position for taking out or replacing music;

Fig. 4, is a plan of one of the movable music roll holders showing one music roll held in position;

Fig. 5, is an end elevation of the holder shown in Fig. 4 and with a portion broken away at 5—5—5 of Fig. 4;

Fig. 6, is an end view of the spring clamp for holding the music roll on the holder in Figs. 4 and 5;

Fig. 7, is a top view of Fig. 6.

In the drawings, wherein for the purpose of illustration is shown the preferred embodiment of this invention, the bench comprises a box-like structure forming a compartment with a front panel 2, rear panel 4, end panels 5 and 5, a bottom panel 12 and a top 1, supported at the corners by four legs 6, 6, 6 and 6. Suitable braces for the legs 6, 6 etc. are 14 and 14 and a connecting brace 13.

The top 1 forms a seat and having hinges 3 and 3 secured to its forward end and to the front panel 2 to permit of the opening of the top 1 upwardly to a position 1', Fig. 3, to give access to the compartment and also to permit of the seat assuming an inclined position as shown in Fig. 3.

9 is a rail secured to the rear panel 4 by hinges 22 and 22 where it normally hangs inside of said rear panel 4 as shown in Fig. 3 or where it can be swung on said hinges to a position 9' to support the seat 1 in an inclined position, also shown in Fig. 3.

The roll holders are designated as 12, for the one which is stationary and forms the bottom panel of the bench compartment, and 7 and 8 for the movable one which each hold a smaller number of rolls and have a length slightly less than one-half that of holder 12 for the purpose of removal from said compartment and for revealing the music rolls in the lower holder.

Referring to Figs. 4 and 5, each of the holders are constructed in a similar manner

in that they have a flat bottom portion forming a base, as 7, 8 and 12; two strips forming brackets 17 and 17 with semi-circular openings 15, lined with a suitable material 5 16, as felt, to support a music roll 19, at or near its ends; and spring clamps 18, 18 etc. formed as shown in Figs. 6 and 7 and arranged in a line centrally between brackets 17 and 17 to clamp and hold music rolls 19, 10 supporting them in the bracket openings 15, 15.

The spring clamps 18 hold the music rolls 19 securely in place, keeping them from unwinding without the use of bands or elastics and holding them in a position so the title 21 of each of them can be read directly from the roll. In this manner titles on the rolls on each holder form a filing system so the rolls can be located directly and as 20 readily as by reading a filing card if the correct name is known, and much more readily than by the ordinary filing system when the correct name is not known.

The front and rear compartment panels 2 25 and 4, have grooves 10, 10 and 11, 11 for supporting the roll holders 7 and 8 and which allow the holders to be moved endwise to uncover the rolls located below. The bottom holder 12 is stationary for holding 30 and storing rolls not immediately in use while the upper holders 7 and 8 are movable endwise in either direction and independently of each other and also removable from the compartment. The grooves 10 and 35 10, in front panel 2, are cut away at the places 20 and 20 to allow each of the holders 7 and 8 to be pivoted in the grooves 11, 11 and swing up through the cut away portions 20 and 20 and so be removed from the 40 compartment.

It will be readily understood that any suitable number of removable roll holders may be provided, depending on the size of the piano bench desired. Also for use with 45 a non-automatic piano, the ordinary flat sheet music can be placed on top of the roll holders or suitable plain music holders can be provided having simply a flat base as 7 without the brackets 17 and 17 or the spring 50 clamps 18.

The operation of the bench in use with a non-automatic piano requires no explanation as the top or seat remains in a horizontal or closed position, in the ordinary manner.

55 For use with a player piano the top is raised to a position 1', Fig. 3, and the music roll desired is selected and removed from its holder. The holders 7 and 8 can be moved endwise in their supporting grooves to uncover the rolls in the holder 8 or 12 or either 60 of the holders 7 or 8 can be removed bodily from the compartment by raising the front from groove 10 through the cut away portion 20. The titles on rolls in the holder so removed can then be read directly from the

rolls and the one desired selected and removed at once and the holder with the remaining rolls replaced. This does away with first reading a card for a roll, and of which the name must be known, and then 70 locating the roll from its file.

The rail 9 is then raised from a position 9 (see Fig. 3) to a position 9' and the seat lowered from position 1' to a tilted position 1, when the bench is ready for use.

75 It will be understood that the front or hinged side of the piano bench is the side next to the piano and the side on which the operator sits in playing. The top then, when tilted to position 1, inclines the operator toward the piano. To obtain a new roll of music, the operator grasps the edge of the seat back of him and pulls it to position 1', Fig. 3, as he rises. He can then look down into the bench compartment and expose all 80 of the titles on the rolls by moving the movable holders to right or left, independently of each other, and obtain the roll desired without moving the bench or moving from his place.

85 Having thus described our invention, what we claim is:

1. A piano bench comprising a supporting structure including a compartment open only at its top, legs for sustaining the compartment, a seat hinged at its forward portion above the compartment, a bottom panel for said compartment, brackets fastened to said bottom panel with semi-circular openings for supporting music rolls, and spring 90 clamps to form a curved contact with and hold said music rolls and form a stationary roll holder, whereby said rolls may be clamped and held in a manner of filing with their titles exposed, while in position in 95 said compartment.

2. A piano bench comprising a supporting structure including a compartment with solid front, rear and end panels and open at its top, legs for sustaining the compartment, a seat hinged at its forward portion above the compartment, grooves in said front and rear panels, and a roll holder adapted to be slidably mounted in said grooves, said roll holder having brackets with semi-circular 100 openings for supporting and spring clamps to form a curved contact for holding said music rolls, substantially as described.

105 3. A piano bench comprising a supporting structure including a compartment with solid front, rear, end and bottom panels and open at its top, legs for sustaining the compartment, a seat hinged at its forward portion above the compartment, said bottom 110 panel having brackets with semi-circular openings and spring clamps to form a curved contact for music rolls to form a stationary roll holder, grooves in said front and rear panels, a movable music roll holder 115 approximately one-half the size of said sta- 120 125 130

tionary holder adapted to be slidably mounted in said grooves, one of said grooves cut away to allow removing said movable roll holder from said compartment, and
5 means on said movable roll holder to clamp and hold music rolls in such a manner that with their titles they form a suitable filing system.

In testimony whereof, we hereby subscribe our names in the presence of two witnesses.

GEORGE J. RAUPP.
DAVID CORNFOOT.
